BED HEADBOARD OR SIMILAR ARTICLE

Richard George Barr, Watchung, N.J., assignor to Thomasville Furniture Industries, Inc., Thomasville, N.C., a corporation of North Carolina

Filed Oct. 11, 1966, Ser. No. 4,241

Term of patent 14 years

(Cl. D5—4)

FIGURE 1 is a front elevation of the bed headboard or similar article embodying the new design; and

FIGURE 2 is a side elevation of the bed headboard or similar article, embodying the new design.

The design is characterized by the configuration of the leg members in combination with the particular moulding, all as shown. The back of the headboard is completely plain and, accordingly, no claim is made to any design feature thereof.

I claim:

The ornamental design for a bed headboard or similar article, as shown and described.
